(57) **CLAIM**

The ornamental design for a aluminum foil pan, as shown and described.

DESCRIPTION

FIG. 1 is a perspective view of a aluminum foil pan, showing the first embodiment of my new design;

FIG. 2 is another perspective view thereof;

FIG. 3 is a front elevational view thereof, the rear elevational view is identical;

FIG. 4 is a left side view thereof, the right side view is identical;

FIG. 5 is a top plan view thereof;

FIG. 6 is a bottom plan view thereof;

FIG. 7 is a perspective view of a aluminum foil pan, showing the second embodiment of my new design;

FIG. 8 is another perspective view thereof;

FIG. 9 is a front elevational view thereof, the rear elevational view is identical;

FIG. 10 is a left side view thereof, the right side view is identical;

FIG. 11 is a top plan view thereof;

FIG. 12 is a bottom plan view thereof;

FIG. 13 is a perspective view of a aluminum foil pan, showing the third embodiment of my new design;

FIG. 14 is another perspective view thereof;

FIG. 15 is a front elevational view thereof, the rear elevational view is identical;

FIG. 16 is a left side view thereof, the right side view is identical;

FIG. 17 is a top plan view thereof;

FIG. 18 is a bottom plan view thereof;

FIG. 19 is a perspective view of a aluminum foil pan, showing the fourth embodiment of my new design;

FIG. 20 is another perspective view thereof;

FIG. 21 is a front elevational view thereof, the rear elevational view is identical;

FIG. 22 is a left side view thereof, the right side view is identical;

FIG. 23 is a top plan view thereof; and,

FIG. 24 is a bottom plan view thereof.
